ELECTRIC MOTOR DRIVEN SILVER POLISHER

William A. Beck, Milwaukee, and William F. Kruke, Cedarburg, Wis., assignors to Beck, Inc., a corporation of Wisconsin

Filed June 6, 1960, Ser. No. 60,852

Term of patent 14 years

(Cl. D9—2)

The single figure of the drawing is a side and end perspective view of an electric motor driven silver polisher embodying our new design, and the opposite side and end perspective view of the unit is precisely the same as that illustrated.

We claim:

The ornamental design for an electric motor driven silver polisher, substantially as shown and described.
